WITNESS:

UNITED STATES PATENT OFFICE.

THOMAS E. ELLIS, OF PORTLAND, OREGON.

SAW.

Application filed January 16, 1922. Serial No. 529,612.

To all whom it may concern:

Be it known that I, THOMAS E. ELLIS, a citizen of the United States, residing at Portland, in the county of Multnomah and State 5 of Oregon, have invented new and useful Improvements in Saws, of which the following is a specification.

This invention relates to compound tools, and comprehends the association with a saw 10 blade, of an adjustable tool and spirit levels, while the blade itself is designed to provide a square, the general construction being such to permit the tool to be very conveniently used for such purposes.

Another important object of the invention 15 resides in the construction of a saw blade to support the handle thereof for sliding movement toward or away from the saw, and also allow it to be arranged at an inclination thereto, the blade being further constructed 20 to permit the rule and spirit levels to be conveniently associated with or removed therefrom as the occasion requires.

The nature and advantages of the invention 25 will be better understood when the following detailed description is read in connection with the accompanying drawings, the invention residing in the construction, combination, and arrangement of parts as 30 claimed.

In the drawings forming part of this application, like numerals of reference indicate similar parts in the several views, and wherein:—

35 Figure 1 is a side elevation of the tool constructed in accordance with the invention;

Fig. 2 is a sectional view taken on line 2—2 of Fig. 1;

40 Fig. 3 is an enlarged fragmentary view showing the extended position of the rule;

Fig. 4 is a sectional view taken on line 4—4 of Fig. 1;

45 Fig. 5 is a view showing the adjusted position of the handle; and

Fig. 6 is a fragmentary view of the saw blade with the handle rule and levels removed.

Referring to the drawings in detail, 50 indicates a saw blade of well known construction having a substantially straight edge 11, and formed at one end to provide an extension 12, the latter rising from the edge 11 and cooperating therewith to define 55 a square. The rear end of the blade is cut away as at 13 to provide a space for the

handle 14, the handle being positioned between parallel flanges 15. These flanges are slotted as at 16 to accommodate the element 17 which passes through the slot and engages the handle to hold it in a given position. The handle 14 by reason of this construction can be moved toward or away from the blade, or arranged at an angle with relation thereto as clearly illustrated. The extension 12 above referred to is provided with substantially right-angularly disposed slots 18 and 19 respectively, and from the ends of each slot project the lugs 20. The spirit level 21 is arranged between one set 70 of lugs and the level 22 is arranged between the other pair of lugs, so that these devices can be viewed from either side of the saw. These devices are held between the lugs by suitable set-screws or the like indicated at 23. The extension 12 is provided with a slot 24 which extends part way across the blade 10, this slot receiving fastening elements 25 which also pass through the rule 26, the latter being suitably graduated 80 as at 27. Nuts 28 are associated with said fastening elements so that when they are tightened, the rule is held fixed relatively to the extension in its adjusted position. Manifestly, I have devised a compound tool 85 which can be conveniently handled and used in the several capacities enumerated, the tool in its entirety being very simple in construction, and cheap to manufacture.

While it is believed that from the foregoing description, the nature and advantages of the invention will be readily apparent, I desire to have it understood that I do not limit myself to what is herein shown and described, and that such changes may be 95 resorted to when desired as fall within the scope of what is claimed.

What I claim is:—

1. In combination, a blade, an extension projecting from one edge of the blade and 100 having a slot extended partly across the blade, said extension together with the adjacent edge of the blade defining a square, a rule arranged at one side of the blade and slidably mounted upon said extension, and 105 fastening elements passed through the rule and said slot for holding the rule fixed relatively to the extension in any adjusted position.

2. In combination, a blade, a handle therefor, an extension projecting from one edge 110 of the blade and cooperating therewith to

define a square, a rule slidably supported by said extension, means for holding said rule fixed relatively to the extension in an adjusted position, said extension having slots disposed substantially at a right angle, lugs projecting from the opposed ends of each slot, a level arranged between each set of lugs, and set-screws associated with said lugs for holding said levels in position upon the extension.

3. In combination, a blade having a cut-away portion at one end thereof, a handle

arranged in said cut-away portion, spaced parallel flanges supporting said handle, said handle being associated with said flanges 15 for sliding or tilting movement, an extension projecting from one edge of the blade and defining therewith a square, a rule slidably mounted on the extension, and means for holding said rule fixed relatively to the 20 extension in an adjusted position.

In testimony whereof I affix my signature.

THOMAS E. ELLIS.
